UNITED STATES PATENT OFFICE.

WILLIAM J. SMRCKA, OF CHICAGO, ILLINOIS.

CHIMNEY-TOP.

SPECIFICATION forming part of Letters Patent No. 395,010, dated December 25, 1888.

Application filed October 9, 1888. Serial No. 287,637. (No model.)

To all whom it may concern:

Be it known that I, WILLIAM J. SMRCKA, of Chicago, county of Cook, and State of Illinois, have invented certain new and useful Improvements in a Chimney-Top, of which the following is a full, clear, and exact description, that will enable others to make and use the same, reference being had to the accompanying drawings, forming a part of this specification.

The object of this invention is to provide a device that will cut up the diverse currents of air and prevent the wind from blowing down the smoke-passage, and also increase and quicken the draft of chimneys and smoke-stacks.

Figure 1 is a side elevation of a device embodying my improved features; Fig. 2, a vertical longitudinal section, and Fig. 3 a plan.

In the drawings, A represents a flue or body of a cylindrical form, which will ordinarily be mounted on the top of a chimney stack or pipe in a stationary position.

To the upper part of the body A are rigidly secured a number of tubular segmental parts, B, arranged vertically around the exterior circumferential surface. The segments B will usually be four in number, and be disposed at regular intervals, as shown. A greater or less number may be used, in accordance with the diameter of the smoke-passage and the results attained. These segments are cut away at both ends on an oblique angle, the lower ends being cut away in a downward direction and the opposite ends upward, leaving the same projecting some distance above the edge of the body A. This arrangement provides air-passages a between the segments and the flue-body, so that the air-currents striking the surface below the segments will naturally be drawn upward around the smoke-passage and have a tendency to increase the draft.

C represents the upper series of wings, and C' the lower companion series. The flanged ends of these wings overlap in the center or back of the segments B, and are riveted or otherwise rigidly secured thereto. These wings are so disposed as to cover the hollows formed between the segments, as shown in Fig. 3. The upper and lower edges of the wings C are cut away at an oblique angle in an upward direction, the edges of the companion series being also beveled, but are

placed in a reversed position, providing the oval opening a', formed between the inner edges of the two series of wings. The highest point of the wings C extends above the top of the segments, while the lowest point of the series C' is below that of the lower end of the segments.

The frustum-ring D is mounted upon and rigidly secured to the highest points of the tubular segments B by means of the brackets b. This arrangement provides the triangular openings d, inclosed by the upper beveled edges of the segments B and the lower edge of the ring D. The openings d are in the same plane with the oval openings a', so that a current of air entering the last-named openings strikes the rounded surfaces of the segments B, naturally passing upward and outward through the angular openings and the space between the upper series of wings and the ring D, being of course also aided by the air-currents entering lower down. The whole is topped by the disk-cap D', rigidly mounted on the upper ends of the brackets b, leaving quite an open space between said cap and the frustum-ring D. The diameter of the cap D' is less than that of the circle described by the series of wings C.

By this form of construction and arrangement of the several parts a chimney top or cap is provided that will have the effect of cutting up and dividing diverse currents of air, and not only thereby preventing the wind from passing down the smoke-passage, but also will have the effect of increasing a sluggish draft and cure "smoky chimneys."

Having thus described my invention, what I claim, and desire to secure by Letters Patent, is—

A chimney-top consisting of the body A, the tubular segments B, rigidly secured to the exterior surface of said body and having both ends cut away, as described, the series of wings C C', having beveled edges and rigidly secured to said segments, and so disposed as to cover the hollows between the same, the frustum-ring D, the brackets b, and the disk-cap D', all constructed and arranged substantially as and for the purpose set forth.

WILLIAM J. SMRCKA.
